CLAIM

The ornamental design for foldable work creeper as shown and described.

DESCRIPTION

1. Foldable work creeper

1.1: Front perspective

1.2: Back perspective

1.3: Front

1.4: Back

1.5: Left

1.6: Right

1.7: Top

1.8: Bottom

1.9: Unfolded

1.10: Enlarged

The dash-dash broken lines shown in the drawings depict portions of the foldable work creeper that form no part of the claimed design.

The dot-dash broken lines in 1.2 and 1.10 are for the purpose of depicting enlarged portions and form no part of the claimed design.
